(57) **CLAIM**

The ornamental design for an LED lamp as shown and described.

DESCRIPTION

FIG. 1 is a front and right perspective view of a LED lamp showing my new design;

FIG. 2 is a bottom and rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircled portion 9 of FIG. 1; and,

FIG. 10 is an enlarged view of an encircled portion 10 of FIG. 2.

The broken lines shown in the drawings depict portions of the LED lamp that form no part of the claimed design.

The LED lamp is shown with a symbolic break in its length. The appearance of any portion of the article between the break lines forms no part of the claim.

1 Claim, 10 Drawing Sheets
